UNITED STATES PATENT OFFICE.

CHARLES E. BAKER AND EVERETT M. DE LONG, OF HARTFORD, CONNECTICUT, ASSIGNEES, BY MESNE ASSIGNMENTS, TO THE NEW BRITAIN MACHINE COMPANY, OF NEW BRITAIN, CONNECTICUT, A CORPORATION OF CONNECTICUT.

INTERNAL-COMBUSTION ENGINE.

1,138,831.

Specification of Letters Patent. Patented May 11, 1915.

Application filed August 23, 1910. Serial No. 578,535.

To all whom it may concern:

Be it known that we, CHARLES E. BAKER and EVERETT M. DE LONG, citizens of the United States, and residents of Hartford, in the county of Hartford and State of Connecticut, have invented a new and Improved Internal-Combustion Engine, of which the following is a specification.

Our invention relates to the class of engines in which force against the piston is obtained by ignition in the cylinder of a charge of mixed air and fuel, and the objects of our invention, generally speaking, are to provide a device of this class which shall have increased efficiency over prior devices.

One form of apparatus embodying our invention and in the use of which the objects sought may be attained is illustrated in the accompanying drawings, in which—

Figure 1 is a view in side elevation of an engine embodying our invention, the engine being shown as attached to the frame of a motorcycle. Fig. 2 is a detail view in central longitudinal section through one of the valve cases showing the arrangement of the parts therein, the valve being at low tension. Fig. 3 is an end view of said valve case, the cap being removed. Fig. 4 is a detail view showing a manner of connecting up the operating levers. Fig. 5 is a view partly in cross-section through the crank casting on plane passing between the cylinders, the valves being shown as under high tension. Fig. 6 is a detail view illustrating the connection with an arrangement of the throttle lever, this view clearly illustrating the arrangement which is more or less indistinct in Fig. 1, owing to the scale.

The invention shown and described herein is adapted for use in engines of various types and constructions, but as we have found it to operate successfully in connection with the type and construction of engine shown in our co-pending application filed July 8, 1910, of Serial Number 570,949 we have selected that device, which is adapted for use in a motorcycle, for the purpose of illustration and description of our

invention herein, the invention, in fact, being an improvement upon the valve mechanism shown in said application, and reference is hereby made to said application, if necessary, for an understanding of the construction and operation of such parts, not embodying our invention, as may not be clear from the illustration and description.

In the accompanying drawings the numeral 7 denotes a portion of the lower frame member of a motorcycle and 8 a portion of an upper frame bar or strut arranged to receive and support the engine employed for driving the vehicle.

The engine, briefly described, consists of a combined crank and transmission case 9 secured to the lower frame member 7 and cylinders 10 located upon the crank case, the cylinders being supported by the upper frame bar 8. A carburetor 11 is located adjacent to the cylinders from which carburetor a supply pipe 12 extends to the intake passage of the engine. The cylinders contain pistons with pitmen connecting the pistons with a crank shaft, the latter being suitably connected with a driving shaft 13 connected with the driving wheel of the vehicle. A pump 14 is located at the end of the casing and a magneto 15 upon the casing, a fly-wheel 16 being secured to the crank shaft. All of the parts above mentioned are arranged and operate substantially as shown and described in our co-pending application above mentioned.

More specifically speaking, the crank case 9 embodies an intake casing 17 to which the supply pipe 12 is connected, this intake casing having an intake passage 18 communicating with an intake chamber 19 located in the crank casing substantially midway between the cylinders. Valve casings 20-21 are formed as a part and located on opposite sides of the crank case, as shown herein the valve casing 20 being located on the lefthand side of the machine and the valve casing 21 on the righthand side of the machine. As the mechanism contained in both of the valve casings is substantially alike, the description herein where it may

relate to a single valve will be considered as applying equally to both.

A valve port 22 opens from the intake chamber 19 into a valve chamber 23 located in each of the casings 20-21, and a passage 24 extends from each of the valve chambers to the cylinder having its supply controlled by the valve in said chamber. A distributing valve 25 rests against a valve seat 26 in each of the valve chambers, each of the valves having a projection extending toward the other valve and supported by a bearing 28, the preferred form of arrangement being as shown in our co-pending application above mentioned, in which one of the projections as 27 extends within the other projection as 36. The projection 36 is tubular for a distance from its end and bears directly within the bearing 28. Each of the valves has a valve stem 29 projecting toward the outer end of the casing and supported by a bearing plate 30 adjustably secured, as by means of interengaging screw-threads, within the casing. A plate stem 31 extends from each of the bearing plates, each stem being hollow and a valve stem projecting thereinto. Webs 32 are provided as means for turning the bearing plates. A closing plate 33 is secured, in any suitable manner, holes for the reception of screws being shown herein, to the outer end of each valve casting to close the opening thereinto.

When the successive movement of the several valves occurs with rhythm a much more increased efficiency is obtained than when the successive movements of the several valves are uneven. The movements of the valves being influenced by the springs, in order to secure a perfect rhythmic movement it is essential that the tension of the springs 34 may be adjusted while the engine is running, as a comparison may then be made and accurate rhythmic movement thus secured. The construction herein illustrated and described as well as that shown and described in our prior application above referred to enables the adjustment to be made at such time, the plate 33 being removed and the bearing plate 30 turned to effect the proper adjustment, this plate preventing escape of any of the fluids employed in driving the engine. The valve mechanism may be thus "tuned" to work in perfect harmony one valve with the other.

We have discovered that the speed of the engine is greatly influenced by a change in tension of the valve springs, and that by increasing the tension of the springs the speed of the engine will be increased. We have further discovered that this increase in the tension of the springs beyond a certain point must take place after the engine has been started, as it is impossible to start the

engine with a tension upon the spring beyond a certain amount. Many different forms of mechanism for accomplishing this result are contemplated by us, that herein shown having been found to produce satisfactory results. In constructing this mechanism a movable spring support 37 is provided for each of the springs 34, these supports being located within the valve chambers 23 and preferably within recesses on the inner surface of the bearing plates 30. A supporting bar 38 extends from each of the spring supports through the plate stems 31, the outer ends of these bars being formed into racks 39. Lengthwise openings 40 extend within each of the bars for the reception of the stem of the valve appurtenant thereto, which has a bearing and is movable within the opening to allow operation of the valve. The outer end of each bearing plate stem is provided with a stuffing box construction 41 through which the bars 38 extend.

Each closing plate 33 has a projection 42 with a slot therethrough forming ears 43 constituting bearings for a pinion 44. The teeth of each pinion is in mesh with the teeth with the teeth of a rack bar 38 and also with the teeth of an operating bar 45 normally forced in one direction as by means of a spring 46. A rod 47 connects each of the operating bars 45 with a valve spring operating lever 48 secured to a lever shaft 49 mounted in a bearing 50 secured to the upper frame bar or strut 8.

A connecting bar 51 is secured to the lever 48 and forms a part of the connection with the operating means, as the handle or grip of the vehicle, the rest of the connection of which may be as by means of a cord 52.

While we do not limit our invention to operation of the valve spring tensioning mechanism at any special time with respect to the operation of the engine, yet we have found material advantage in operation to follow when the tensioning of the spring is simultaneous with the increase of the speed of the engine from other sources. To attain this result the bar 51 is attached to the throttle lever 53 and the connection 52 is attached to the bar 51, so that as the throttle lever is moved to control the operation of the engine the spring tensioning mechanism will be operated simultaneously therewith.

We have further found that in some instances at least, if not all, it is important to have the engine attain considerable speed before any tension is placed upon the valve springs. To secure this result a slot and pin connection is formed between the valve spring operating lever 48 and the connecting bar 51, as shown herein a slot 54 in the bar 51 receiving a pin 55 from the lever 48.

By means of this construction, in starting the engine the bar 51 will be moved to a certain extent and the throttle lever operated to admit fuel before operation of the tensioning mechanism.

We do not limit our invention and the scope of the following claims to the foregoing illustration and description of the preferred form of mechanism in which the invention is shown as embodied, as this construction may be departed from to a greater or lesser extent without avoiding the invention.

We claim—

15. 1. A cylinder, a piston located in the cylinder, a valve chamber communicating with the cylinder, an intake valve to control the supply of fluid to the cylinder, means for exerting force to hold said valve to its seat, means for controlling admission of fluid to said valve, and means for simultaneously operating said fluid admitting means and also for varying the pressure against said valve.
20. 2. A cylinder, a piston located in the cylinder, a chamber communicating with the cylinder, a valve in said chamber to control the flow of fluid to the cylinder, a spring exerting pressure upon the valve, means for controlling the admission of fluid to said valve, and means for simultaneously operating said fluid controlling means and also for varying the tension upon said spring.
25. 3. A cylinder, a piston located in the cylinder, a valve chamber communicating with the cylinder, a valve located in said chamber, means for exerting force to press the valve to its seat, a throttle to control the admission of fluid to said valve, and means connected for operation with said throttle to vary the force to hold the valve to its seat.
30. 4. A cylinder, a piston located in the cylinder, a valve chamber, an intake valve located in said chamber, a spring to force said valve against its seat, a throttle to control the admission of fluid to said valve, and means for varying the force of said spring, said means being connected for operation simultaneously with the throttle.
35. 5. A plural number of cylinders, pistons located in each of the cylinders, a valve chamber communicating with each of the cylinders, an intake valve located in each of the chambers, means for forcing each of the valves to its seat, means to control the admission of fluid to each of the valves, and means connected to operate simultaneously with the fluid admitting means to vary the force against said valve.
40. 6. A plural number of cylinders, a piston located in each cylinder, a valve chamber communicating with each chamber, a spring to force the valve to its seat, and means arranged to increase the tension of the spring in proportion to an increase in the amount of fuel admitted.
45. for forcing each of the valves to its seat, means for controlling admission of fluid to the valves, and means connected to operate simultaneously with the fluid admitting means to vary the tension upon said springs.
50. 7. A cylinder, a piston located in the cylinder, a casing inclosing a valve chamber, an intake valve located in said chamber, a spring within said chamber to force said valve against its seat, means inclosed in said casing for varying the tension upon said spring, and a second means for varying the tension upon said spring to increase the speed of the engine.
55. 8. A pair of cylinders, a piston located in each of the cylinders, a valve chamber appurtenant to each of the cylinders, an intake valve located in each of said chambers, a spring in each of said chambers to force each of the valves to its seat, means for varying the pressure upon each of the springs, and a second means appurtenant to each spring and connected to operate simultaneously to vary the pressure upon said springs to increase the speed of the engine.
60. 9. A plural number of cylinders, a piston located in each cylinder, a valve chamber communicating with each cylinder, a valve located in each chamber, a spring pressing each valve against its seat, means for varying the pressure upon each spring, a second means connected to operate simultaneously to vary the pressure upon said springs, and means to control the fluid admission and connected to operate simultaneously with the spring tensioning means.
65. 10. A cylinder, a piston located in the cylinder, a valve chamber communicating with the cylinder, an intake valve located in said chamber, means within said chamber arranged to force the valve against its seat, mechanism extending outside of the chamber to operate the means to force the valve against its seat to vary its tension, and means for operating the pressure controlling mechanism.
70. 11. A cylinder, a piston located within the cylinder, a valve chamber, an intake valve located within said chamber, a spring to force said valve against its seat, a plate closing the valve chamber and adjustable to vary the tension upon the spring, a second plate in engagement with the spring and with said plate and movable independently of the latter, and means extending to the outside of said chamber for operating the spring tensioning device.
75. 12. A cylinder, a piston located therein, a valve to control the admission of fluid to the cylinder, means for forcing the valve to its seat, and means arranged to increase the tension of the spring in proportion to an increase in the amount of fuel admitted.

13. A cylinder, a piston located therein, a valve to control the admission of fluid to the cylinder, means for tensioning said valve, means for varying the degree of said tension, a throttle to control the flow of fluid to the engine, and a connection between said throttle and the valve tensioning members to operate the latter simultaneously with the operation of the throttle.
